(57) **CLAIM**

The ornamental design for a diaper backpack with bed, as shown and described.

DESCRIPTION

FIG. 1 is a front and left perspective view of a diaper backpack with bed, showing my design.

FIG. 2 is a rear and right perspective view thereof.

FIG. 3 is a front elevation view thereof.

FIG. 4 is a rear elevation view thereof.

FIG. 5 is a left side elevation thereof.

FIG. 6 is a right side elevation thereof.

FIG. 7 is a top plan view thereof.

FIG. 8 is a bottom plan view thereof; and,

FIG. 9 is a perspective view of the diaper backpack with bed in a folding state.

The broken lines showing zipper track, toggles and a handle fastening strap depict environment and from no part of the claim.
